FIG. 3.

FIG. 4.

FIG. 5.

INVENTOR:

HENRY E. WIEDMANN.

BY
Baldwin Hale

ATTORNEY.

UNITED STATES PATENT OFFICE

HENRY E. WIEDMANN, OF SAN FRANCISCO, CALIFORNIA

POLISHER

Application filed December 6, 1930. Serial No. 500,507.

This invention relates to improvements in polishers and more particularly to polishers and honers for pivots of horological and similar instruments.

5 The principal object of the invention is to automatically maintain precision in the shape and size and to eliminate risk of breakage of delicate pivots during the polishing operation.

10 Another object is to prevent undue friction of the polisher against the work.

Another object is to place the polishing member against the lower side of the work so that the progress of the polishing operation 15 may be readily observed by the operator.

A further object is to permit inspection or removal of the work without readjustment of the polisher.

In this description and the accompanying 20 drawing, the invention is disclosed in its preferred form; but it is to be understood that it is not limited to this form because it may be embodied in other forms. It is also to be understood that in and by the claims following the description it is desired to cover 25 the invention in whatsoever form it may be embodied.

In the accompanying one sheet of drawing:

30 Fig. 1 is a side elevation partly in section showing one form of the invention applied to a conventional watchmakers lathe.

Fig. 2 is a front elevation of the same.

Fig. 3 is a detail view in front elevation of 35 one form of watch pivot being polished in accordance with this invention.

Figs. 4 and 5 are similar views of two other forms of watch pivots and the shapes of the polishing members used in conjunction therewith.

40 Fig. 6 is a vertical section of the resilient mounting of the polishing bar.

In detail, the construction illustrated in the drawing is applied to a conventional watchmakers lathe which comprises the cylindrical bed 1 mounted on the sliding block 2. The block 2 is adjustably mounted in the base 3 which may be securely fixed to a work bench (not shown). The head stock 4 is secured to the bed 1 and is provided with the

journals 5—6 to carry the shaft 7. The usual step pulleys 8 are fixed to the shaft 7 and are adapted to be driven by a belt from a suitable prime mover.

The spindle stock 9 is mounted on one end of the shaft 7 and carries the chuck 10. Watch wheels and balance pivots are held in the chuck by the jam nut 11 in the usual manner.

45 The polishing device is substituted for the conventional tool rest when in use. The tool rest base 12 is slidably mounted on the bed 1 so as to be capable of longitudinal adjustment. The intermediate plate 13 is slidably mounted on the plate 12 and may be laterally adjusted.

50 The plates 12 and 13 are locked in their respective adjusted positions by the bolt 14 having the round head 16 which is confined in the groove 17 of the plate 13. The bolt 14 is tightened by the handle 18 threaded on the end thereof. This jams the overlying plate 13 and the base plate 12 against the bed 1.

55 The plate 19 is slidably mounted on the interlocking lug 20 of the intermediate plate 13. The shim 21 is inserted in the plate 19 alongside the lug 20 to assure an accurate fit. The shim is held in place by the screw 22 and may be adjusted by the setscrews 23—23.

60 The standard 24 is fixed to one end of the sliding base 19. The polishing bar 25 is fulcrumed on the screw 26 which is threaded in the upper end of the standard 24. The spring 27 encircles the body of the screw and expands between the head of the screw and the polishing bar 25. The bar thus is adapted to swing laterally against the tension of the spring 27.

65 The setscrews 26—26' are provided in the standard 24 above and below the screw 26 and bear on the bar 25. These permit lateral adjustment of the bar 25 with respect to its vertical plane and maintains the horizontal top plane of the bar at the desired angle to the axis of the pivot 30.

70 The bar 25 is provided with the extension 28 on the opposite side of the fulcrum 26. The weight 29 is adjustably mounted thereon and its gravity raises the edge of the bar 25 100

until it contacts the pivot 30 of the watch wheel 31 inserted in the chuck 10 of the lathe. It is obvious that a spring counterbalance may be substituted for the weight 29. The 5 edge of the polisher 25 maintains its set angle with respect to the watch pivot 30 and remains so during the entire polishing operation. The usual polishing material is applied to the working edge of the bar 25, if 10 desired.

The invention operates substantially as follows: The lathe is driven through the pulley 8 to rotate the watch wheel pivot 30 in the chuck 10. The plates 12, 13 are adjusted by loosening the handle 18 to align the 15 polishing member 25 with the watch pivot 30.

The resilient mounting of the bar 25 against the spring 27 facilitates the placing of the polisher 25 in position under the pivot 30.

Undue friction of the polishing edge against the shoulder 35 of the pivot does not occur, as the bar 25 recedes against the tension of the spring 27.

The bar 25 is reciprocated longitudinally 25 by the operator grasping the knob 32 and manually moving the sliding base 19. The weight 29 causes the polisher 25 to bear against the pivot 30 with a uniform pressure. This pressure may be regulated by adjustment of the weight along the bar as desired.

One of the lower corners of the polishing member is chamfered as at 33. When a watch pivot of the type shown in Fig. 4 is to be polished, the position of the polisher 30 is reversed by removing the screw 26 and reversing the bar 25 to bring the chamfered edge 33 against the fillet 35' of the watch pivot 30'.

Fig. 5 shows a beveled watch pivot 30" and the bar for polishing it. In this case, the working edge of the polisher 25" is beveled as at 34" to align with the pivot 30". The shoulder 35" is provided adjacent the bevel to seat on the horizontal portion 36 of the shaft of the watch wheel. This effectually prevents the polisher from slipping off the inclined surface 30" under the pressure of the weight 29.

The device may be used as a honer or 50 grinder for pivots by distributing an abrasive substance along the working edge of the polishing member 25. The pivot is then honed or lapped by substantially the same operation as for polishing. By this method, 55 pivots may be effectively straightened or reduced in diameter.

Having thus described this invention, what I claim and desire to secure by Letters Patent is:

60 1. In combination with a lathe, a sliding base having a standard thereon; a counterbalanced polishing bar on said standard pivoted parallel to the axis of the work in the lathe and capable of resilient movement longitudinally in respect to said work.

2. In combination with a lathe, a sliding base having a standard thereon and mounted on the bed of said lathe, a counterbalanced bar loosely pivoted on said standard and bearing against the work in said lathe, and resilient means pressing against the side of said bar.

3. In combination with a lathe; a base 75 slidable transversely to the axis of the work in the lathe; a standard fixed on said base; a counterbalanced polishing bar loosely pivoted to said standard, said pivot being parallel to the axis of said work, resilient means pressing said bar against said standard; and 80 projections in vertical alignment above and below said pivot on said standard and abutting the side of said bar to form an auxiliary fulcrum to permit said bar to resiliently swing longitudinally of the axis of said work.

4. In combination with a lathe; a base 85 slidable on the lathe bed transversely to the axis of the work in the lathe; a standard fixed on said base; a counterbalanced polishing bar 90 loosely pivoted to said standard, said pivot being parallel with the axis of said work; setscrews in vertical alignment above and below said pivot in said standard and adjustable to vary the angle of the top plane of said bar in respect to said work, and resilient means pressing said bar against said set-screws.

In testimony whereof I have hereunto set my hand this 26th day of November, 1930.

HENRY E. WIEDMANN.
